UNITED STATES PATENT OFFICE.

MATHEW J. BEAVER, OF LOYAL, WISCONSIN.

WASHING MACHINE.

Application filed September 18, 1920. Serial No. 411,040.

To all whom it may concern:

Be it known that I, MATHEW J. BEAVER, a citizen of the United States, residing at Loyal, in the county of Clark and State of Wisconsin, have invented certain new and useful Improvements in Washing Machines, of which the following is a specification.

The purpose of the present invention is to provide an improved clothes washing machine in which an alternating rotary movement is given to the clothes rubber which, at the same time, is automatically and vertically reciprocated upon the clothes with a rubbing and beater action calculated 15 to most effectually cleanse the clothes during the operation of the machine.

An additional object is to provide an improved type of washing machine in which the rubber element is reciprocated through 20 the direct action of a rotatable operating shaft and its crank portion without the interposition of gears between the rubber and the shaft.

A further object is to provide a washing 25 machine of simple and economical construction, designed to be easily operated and capable of being readily taken apart for repairs or cleaning whenever desired.

With the above and other objects in view, 30 the invention may be said generally to reside in the details of construction, combination and arrangement of parts as will be herein-after more fully pointed out, reference being had to the accompanying drawings, 35 wherein—

Figure 1 is a top plan of a machine constructed in accordance with the invention.

Figure 2 is a vertical cross sectional view taken on line 2—2 of Figure 1.

Figure 3 is a similar view taken on the 40 line 3—3 of Figure 2 and disclosing the bend or crook forming the crank portion of the operating shaft, and

Figure 4 is a vertical longitudinal sec- 45 tional view of the movable cross head of the rocker element.

In the drawings, the numeral 1 represents 50 a tub or other suitable washing receptacle in which the clothes are deposited, such receptacle being adequately supported by suitable under supporting structure or legs 2. The tub is provided with a cover 3 to one side of which a door 4 is hingedly connected. The cover and door fit into a socket 55 or recess formed upon the inner face of the tub sides and adjacent the upper edge as

indicated at 5. Access to the interior of the tub is permitted only through the opening of the hinged door, which however, may be readily swung back when desired. 60

A clothes rubber is provided and consists in a disk like head 6 having a plurality of blunt projections or fingers 6' depending from the under face thereof, the head being carried by a stem or shaft 7 inserted 65 through a guide opening 8 in the center of the cover and provided adjacent its upper end with an enlargement recessed to provide a seat or saddle 9 for the bow 10 of the oscillating rocker element. The bow or 70 rocker 10 is mounted between the ears or flanges 11 of the saddle and is pivotally retained in place by means of a bolt or other suitable fastener 12. When actuated this rocker is designed to tilt from side to side 75 for a purpose to be hereinafter explained. Arranged between the ends of the rocker is a cross head or connecting member 13 preferably cylindrical in cross section and provided with an extension or laterally off- 80 set portion 14 as illustrated. A bore 15 extends centrally through the offset and transversely across the member with respect to the longitudinal axis of the latter. At its ends of the cross head is provided with 85 socket recesses 16 for the reception of pivot members 17, the latter being adjustably threaded through the ends of the rocker.

A pair of supporting standards or brackets 18 are arranged in alignment, upon one 90 side of the central guide opening 8 of the cover and are secured to the latter as indicated at 19. These brackets are provided at their uppermost ends with bearings 20 through which the operating shaft 21 is 95 rotatably inserted. Rigid with one end of the shaft is a large wheel 22 provided with a handle or grip 23 by means of which the wheels and shaft may be manually rotated. However, any other suitable means may be 100 employed for rotating the shaft whereby it may be either motor driven or hand operated. Crank means comprising a bend or loop 24 having angularly disposed side portions, one of which is elongated as at 105 25, is formed integral with the shaft and provides the actuating means for the oscillating rocker. The elongated end 25 is inserted through the bore 15 of the movable cross head and is of smaller diameter than the bore so as to be freely movable in a 110 transverse direction therein. In their as-

sembled and operative relation, the parts will be arranged substantially as illustrated in Figure 3 of the drawing. It is contemplated by the invention that in the operation 5 of the machine, the clothes rubber be given a reciprocatory movement in a vertical direction so as to beat or pound upon the clothes while at the same time be oscillated so that the fingers 6 will be alternately 10 rotated about an axis from side to side and in a horizontal plane, thus tending to agitate or churn the hot, soapy water and stirring up the clothes to a sufficient degree. This is accomplished by reason of the novel 15 connection provided between the shaft 7 and the operating shaft 21, and including the crank 24, the rocker 10 and the cross head 13.

Assuming the parts, as illustrated in Figure 3, to be in neutral or starting position, the rotation of shaft 21 correspondingly rotates the crank portion 24 with the forwardly projecting inclined portion 25 of the crank describing a greater circle at its outer 20 than at its inner end, governed of course, by the degree of inclination of the elongated portion with respect to the perpendicular. Considering the shaft as being rotated in a clockwise direction the crank 24 in making 25 the first quarter turn will be brought to a horizontal position, the pivoted cross head or roller 13 moving freely downward with portion 25 as the latter is turned to lie in the same horizontal plane with the shaft 21. It is to be noted from Figure 3 of the drawings that at the start the crank portion 25 extends transversely across the vertical axis of the cross head 13 and at an angle thereto. Consequently, when the shaft is first rotated 30 40 the crank end will be shifted within the bore 15 of the cross head so as to bind against diagonally opposite portions of the bore as indicated at X and Y respectively. As the crank end is turned more and more 45 from its vertically upright position this binding action or pressure increases and since the pressure at X is on one side of the vertical axis of the shaft 7 and rocker 10, tending to be exerted in one direction and 50 the pressure at Y on the opposite side of the axis and exerted in an opposite direction, the tendency is for the rocker 10 to turn about its vertical axis until it has assumed the position indicated by the dotted line 55 structure of Figure 1, with the crank lying in the horizontal plane and completing the first quarter turn. Upon the continued rotation of the operating shaft the pressure at X and Y will of course be respectively exerted upwardly and downwardly on opposite sides of the horizontal axis of the cross head 13 which being pivotally mounted is 60 free to revolve, allowing the crank to turn so that as the bend 24 moves upwardly the 65 inclined portion 25 moves downwardly, the

pressure at X and Y consequently shifting so that at Y it is exerted in a lateral direction tending to move the rocker around, while at X it is exerted in the opposite direction, tending to swing the other end of 70 the rocker around so that by the joint action or pressure at X and Y the rocker and of course the clothes rubber, is swung back or returned to its original starting position, the pressure at X and Y continually shifting 75 until at the completion of the second quarter or half turn the position of the shaft, crank and cross head 13 will be completely reversed. For the third and last quarter turn, the operation is the same as previously described with the exception that it occurs on the reverse side of the vertical axis, the binding action at X and Y turning the rocker to the opposite side of that indicated by the dotted lines of Figure 1, from which 80 position it is returned at the completion of the last quarter or full revolution of the shaft. It will thus be seen that upon one complete turn or revolution of the shaft the rocker and clothes element has been oscillated and to prevent any binding of the crank portion 25 and the cross head 13 which might, in any way affect the operativeness of the device, the rocker 10 is permitted to rock 85 from side to side upon its pivot 11 as the 90 shifting of the crank portion within the bore 15 of the cross head may require. It is further to be noted that as the crank revolves, the portion 25 is continually changing its 95 position and as the crank portion at Y moves 100 up and around, it exerts a lifting force upon the cross head which causes the clothes rubber to be vertically reciprocated through the guide opening 8, the opening tending to hold 105 the clothes rubber steady and firm. The reciprocation of the clothes rubber will of course occur simultaneously with the oscillation of the shaft and rocker element, these movements being rapidly effected upon the 110 continuous rotation of the operating shaft. The movement of the clothes rubber is controlled entirely by the crank portion of the operating shaft and is governed according 115 to the degree of inclination given to the crank portion 25. No gears are required for the transmission from the shaft to the clothes rubber and the lack of gears in no way detracts from the efficiency of the invention.

It is thought that the construction and 120 operation of the machine will be apparent and clearly understood from the foregoing description taken in connection with the drawings and it will be noted from the latter that no extravagant or unnecessary parts 125 are employed to burden the utility or practicability of the invention. It is believed that the advantages of the invention may be readily understood and appreciated from the above disclosures which constitute but 130

one form or application of the invention, it being obvious that with changes and alterations of a minor character the same may be readily adapted for and applied in various 5 and other ways.

Having thus described the invention what I claim as new and desire to secure by Letters Patent is:—

In a driving mechanism for a washing machine comprising a vertically disposed rotatable and reciprocatory work shaft, a substantially semi-circular yoke pivoted at its center to the upper end of said work shaft, a cross bar pivoted to the terminals of said 10 yoke, and a sleeve carried by the central

portion of said cross bar, an operating shaft disposed at right angles to the work shaft, means for operating the operating shaft, and an elongated inclined crank arm formed on the operating shaft and disposed at an angle 20 of substantially 45 degrees to the longitudinal axis of said operating shaft and slidably mounted in said sleeve.

In testimony whereof I affix my signature in presence of two witnesses.

MATHEW J. BEAVER.
